UNITED STATES PATENT OFFICE.

CHARLES WELLS SHARTLE, OF MIDDLETOWN, OHIO.

PULP-REDUCING APPARATUS.

1,173,747.

Specification of Letters Patent. Patented Feb. 29, 1916.

Application filed November 25, 1912. Serial No. 733,267.

To all whom it may concern:

Be it known that I, CHARLES WELLS SHARTLE, a citizen of the United States, residing at Middletown, Butler county, Ohio, 5 have invented certain new and useful Improvements in Pulp-Reducing Apparatus, of which the following is a specification.

This invention relates to a process of and apparatus for reducing pulp, such as is commonly employed in the manufacture of 10 paper.

The object of the invention is to provide a process for continuously reducing the stock or pulp to the required degree of fineness, the fine pulp being automatically separated from the coarse without interrupting the continuous treatment of the coarser pulp; and further, provide an apparatus for carrying out this continuous operation.

Reference may be profitably made to 20 United States Patents Nos. 989,879 of 1911 and 1,011,255 of December 12, 1911 relating to pulp-reducing apparatus invented by me.

The present invention after reference to 25 the above mentioned patents may be readily understood from the following description taken in connection with the accompanying drawings in which:—

Figure 1 is a plan of a pulp-reducing apparatus exemplifying an embodiment of my invention; Fig. 2, a side elevation of the same, both of these figures being of a somewhat diagrammatic character; Fig. 3, a vertical section through the outlet of a beater-tub in the plane of lines *a* of Fig. 1; and Fig. 4, a vertical section of the whirl-pool in the plane of line *b* of Fig. 1.

In carrying out my process I place the 40 stock which is to be reduced in a suitable receptacle or tub, with large quantities of water, and treat the same to reduce it to a pulp of the desired degree of fineness. As will be readily understood, parts of the material will soften and be reduced to the desired fineness more quickly than will other parts of the material, this being particularly true where the stock being worked is old paper stock. As the treatment continues 45 and the portions of pulp reach the desired degree of fineness, I cause the water to overflow from the tub and to carry with it such portions of the stock in suspension therein

as may be of sufficient fineness. This stock which overflows from the tub is then 55 screened or treated to further separate the fine pulp from the coarse pulp, and the coarser portions of this pulp, or tailings, are returned to the tub for further treatment. This process is carried on continuously and 60 without interruption, additional stock and water being added to the tub from time to time to replace those portions thereof which overflow from the tub.

In the accompanying drawings I have 65 illustrated an apparatus for carrying out this process, and this apparatus is also capable of carrying out an amplified process embodying the same steps above described, and other steps. This amplified process consists in first treating the stock to reduce it to pulp, causing the properly reduced pulp to overflow, then subjecting the pulp which has thus overflowed to the action of a digester, then screening the pulp after it 75 leaves the digester and again treating the tailings from the screen to further reduce the same, causing the properly reduced pulp to again overflow and to be again screened. These drawings illustrate one apparatus by 80 means of which the process may be carried out, but is shown here merely for the purpose of illustration, it being understood that various apparatuses may be utilized in carrying out the invention.

1, indicates a breaking engine, of construction similar to a beating engine except that its cylinder is not set close to the bed-plate, the function of this breaking engine being to break up masses of stock such as books, 90 bundles of paper, etc., and reduce the stock to such condition that it may be pumped through pipes; 2, the water-supply pipe for the breaking engine; 3, a low point in the rim of the tub of the breaking engine to 95 form an outlet for broken stock therefrom; 4, a receiver or conduit to receive the outflow from the breaking engine; 5, a pump receiving the stock from conduit 4; 6, a digester, illustrated as of rotary type; 6^a, the 100 discharge pipe from pump 5, the same delivering into the digester; 6^b, a steam pipe communicating with the digester to deliver steam thereto; 7, a trough forming a settling-box; 8, a pipe connected with the digester and delivering to the initial end of 105

the settling-box; 9, a screen, of usual construction and to be provided preferably with means for dragging stock tailward along the screen-plates; 10, a whirl-pool, the same consisting of a circular vessel into which trough 7 delivers tangentially at a point above the floor of the vessel; 11, a fender disposed across the upper portion of the vessel of the whirl-pool and presenting an upper face sloping downwardly toward the side of the vessel into which trough 7 delivers; 12, a trough leading from the upper portion of the whirl-pool to the head of the screen, the connection of this trough with the whirl-pool vessel being on that side of fender 11 opposite the inlet to the vessel from trough 7; 13, a beating engine; 14, the outlet from the tail of the screen into the beating engine; 15, a water-supply pipe to the beating engine; 16, a low point in the rim of the tub of the beating engine to permit of the outflow of the beaten stock therefrom; 17, a receiver or conduit to receive the outflow from the beating engine; 18, a pump to receive the pulp going from the beating engine; 19, the discharge pipe of this pump, the same delivering into the initial end of settling-box 7; 20, a wet machine, comprising a vat and a foraminous cylinder rotat-

ing therein; 21, a conduit to convey to the vat of the wet machine the fine pulp and water which passes through the plates of the screen; 22, the foraminous cylinder of the wet machine; 22^a, the couch-roll of the wet machine; 23, the doctor for the couch-roll; 24, the finished-pulp vat of the wet machine, the same containing an agitator to keep the pulp in fair condition for outflow; 25, the outflow pipe for the finished pulp leaving the wet machine; 26, a pump receiving the water and entrained pulp which has passed into the cylinder of the wet machine; and 27, the discharge pipe of pump 26, the same delivering to trough 7, or elsewhere as desired.

Such paper making stock as old papers and books, is generally in compact bundles and along with this will be mixed much hard material such as iron and glass, and also some very light material, such as cork and wood, which foreign matters should be kept out of the pulp and out of the beating engine which reduces the stock to pulp.

I have found in practice that if stock is circulating in a breaking or beating engine in the presence of large quantities of water, the finest stuff is at the top while swimming in and upon the top of this finer stuff is the coarser stuff such, for instance, as unbroken bundles and books in the breaking engine. The finer stock may overflow from the breaking engine while the coarser or unbroken stock continues to swim along in the circuit.

65 The stock having been placed in the

breaking engine 1 and supplied with large quantities of water the engine breaks up the stock and the tub of the breaking engine being carried sufficiently full to permit overflow, the finer stock overflows through low point 3 in the rim of the tub and goes to the conduit or receiver 4 which delivers it to some part of the apparatus for further treatment. Where the arrangement of the apparatus is such that some part thereof which acts on the stock after it leaves the tub is elevated above the level of the tub, as shown in the present drawings, an elevating device, such as a pump 5, is provided and the receiver delivers the stock to this elevating device. The unbroken masses do not overflow with the fine stuff but continue along in the circuit. Water and stock are to be added to the breaking engine as fast as required to make up for the outflow from the tub. This additional water and stock may be fresh water and fresh stock or it may consist partially or entirely of water and stock which have passed through some part of the apparatus. In the apparatus here illustrated fresh water and stock are added to the breaking engine while the beating engine receives tailings from the screen, as will be hereinafter explained.

The broken stuff from the breaking engine is delivered to the digester by pump 5 and is therein subjected to the action of steam supplied through pipe 6^b. The digester is illustrated as of rotary type but it may be of any desired character adapted to have broken stuff pass through it in the presence of steam. The stuff in passing through the digester has its fibers opened up and separated and upon leaving the digester it goes through pipe 8 to settling-box 7 on its way to the whirl-pool. In passing through the settling-box it deposits therein such heavy impurities as may settle to the bottom of the settling-box but the light floating impurities and also some of the heavy impurities will be carried to the whirl-pool. The stock entering the whirl-pool rotates therein in finding its way to the outlet to the screen. The heavy matters which have succeeded in reaching the whirl-pool will settle therein, while the extra light impurities will be skimmed and arrested by fender 11, the result being that stock going to the screen is practically free from both heavy and light impurities. The heavy impurities settling in the settling-box and whirl-pool, and the light impurities arrested in the whirl-pool may be cleared away from time to time as occasion requires. The stock goes from the whirl-pool to the screen, and such matter as does not pass through the screen-plates goes from the tail of the screen to beating engine 13 whose action is to pulp the stock. The finer stock in the tub of the beating engine

overflows the tub and goes to pump 18 from which it finds its way again to the screen, the sufficiently fine pulp passing through the screen-plates, and the coarser pulp passing as before from the tail of the screen to the beating engine, the coarsest stock in the beating engine swimming around in the tub. The result is that the stock passes over the screen; there is abstracted from it 5 pulp of sufficient fineness to pass through the screen; the tailings of the screen are again subjected to beating action; the finer products from the beating engine go again to the screen, and so on and on and on, the 10 stock coming from the digester to make up for the pulp which has passed through the screen-plates, the operation being continuous.

It will be noted that the overflow of the 20 pulp from both the breaking engine and the beating engine is due solely to the increase of the quantity of stock and water in the tubs, and that no pumping or forcing action of any kind is required. Consequently, I employ open tubs, as distinguished 25 from the casings of those reducing engines in which the reducing element also has a pumping or forcing action which causes the pulp to be discharged from the 30 casing.

Pulp and water which has passed through the screen-plates finds its way through conduit 21 and its connections to the wet machine, where it is picked up by the foraminous cylinder, the water with some entrained pulp passing into the cylinder, while the drier finished pulp is scraped off of the cylinder by the doctor and goes through pipe 25 to any proper point for use or for 40 further treatment. The water and entrained pulp which has passed into the cylinder of the wet machine is taken by pump 26 and is delivered again into the general circuit so that the entrained pulp may be recovered. The water and entrained pulp 45 handled by pump 26 may be so dirty that it is undesirable to let it go back into the circuit to go into the finished pulp and in such case pipe 27, instead of delivering into 50 the circuit may deliver to some point of waste or to some point of utilization of the material where dirtiness is not of special moment.

I claim:—

55 1. A pulp reducing apparatus comprising a reducing engine adapted to reduce the coarseness of the material under treatment and comprising an open tub arranged to permit the material to overflow from it as additional material is deposited therein, and a receiver adapted to receive the overflow from said tub.

2. In a pulp reducing apparatus, a reducing engine adapted to reduce the coarseness

of the material under treatment and comprising an open tub arranged to permit the material to overflow from it as additional material is deposited therein, a screen, a receiver to receive the overflow from the tub, and means for delivering the material from 65 said receiver to said screen.

3. In a pulp reducing apparatus, a reducing engine comprising an open tub arranged to cause portions of the material under treatment therein to overflow, a screen 75 arranged to deliver its tailings to said reducing engine, and means for transferring the pulp which has overflowed to said screen.

4. In a pulp reducing apparatus, a reducing engine comprising an open tub arranged to permit the stuff therein to overflow, a screen arranged to deliver its tailings to said beating engine and conveying mechanism, comprising a pump for transferring the stuff which has overflowed from said 80 engine to said screen.

5. In a pulp reducing apparatus, a breaking engine comprising an open tub arranged to cause the stuff therein to overflow, a beating engine also arranged to cause the stuff 90 to overflow, a screen arranged to deliver its tailings to said beating engine, means to transfer the stuff which has overflowed from said breaking engine to said screen, and other means for transferring the stuff which 95 has overflowed from said beating engine to said screen, whereby said stuff is continuously and automatically acted upon to cause it to be reduced to the proper fineness and the fine pulp to be separated from the coarse. 100

6. In a pulp reducing apparatus, a breaking engine comprising an open tub arranged to cause the stuff therein to overflow, a beating engine also comprising an open tub arranged to cause the stuff therein to overflow, 105 a screen, a settling box to deliver to said screen, and means to transfer the material which has overflowed from said breaking engine and said beating engine to said settling box. 110

7. In a pulp-reducing apparatus, a reducing engine comprising an open tub arranged to permit portions of the material therein to overflow, a receiver arranged to receive the material overflowing from said 115 tub, a screen, and means to deliver the material from said receiver to said screen, said means comprising a pump communicating with said receiver.

8. In a pulp reducing apparatus, a reducing engine arranged to cause the stuff therein to overflow, a screen arranged to deliver its tailings to said reducing engine, a settling box to deliver to said screen, and means to transfer the material, which has 120 overflowed from said reducing engine, to said settling box. 125

9. In a pulp reducing apparatus, a break-

ing engine arranged to cause the stuff there-
in to overflow, a reducing engine also ar-
ranged to cause the stuff therein to overflow,
a screen arranged to deliver its tailings to
5 said reducing engine, a settling box to de-
liver to said screen, and means to transfer
the material which has overflowed from said

breaking engine and said beating engine to
said settling box.
